2 SHEETS—SHEET 2.

UNITED STATES PATENT OFFICE.

RUBEN H. BOYCE, OF GLASCO, KANSAS.

BOX-HOLDER.

1,388,089.

Specification of Letters Patent. Patented Aug. 16, 1921.

Application filed September 9, 1920. Serial No. 409,203.

To all whom it may concern:

Be it known that I, RUBEN H. BOYCE, citizen of the United States, residing at Glasco, in the county of Cloud and State of Kansas, have invented certain new and useful Improvements in Box-Holders, of which the following is a specification.

This invention relates to a machine for use in box making and has for its object 10 the provision of means for supporting the ends and central partition of a box or crate while the sides and bottom are nailed thereto.

The invention seeks to provide means for 15 the stated purpose which will firmly support the box ends and central partition and permit them to be easily turned so that either side or the bottom may be readily secured in place.

20 The invention also seeks to provide a mechanism for the stated purpose which will be free of complicated arrangements or constructions and which may be produced at a low cost and easily manipulated.

25 The several stated objects and other objects which will incidentally appear in the course of the following description are attained in such a mechanism as is illustrated in the accompanying drawings, and the invention resides in certain novel features which will be particularly set forth in the 30 claims following the description.

In the accompanying drawings:

Figure 1 is a perspective view of an apparatus embodying my improvements,

Fig. 2 is an enlarged longitudinal section through one end portion of the machine,

Fig. 3 is an end elevation, illustrating by 40 dotted lines the movement whereby turning of the box or crate is effected.

In carrying out my invention, I employ a table 1 which may be supported upon legs 2 of any preferred form and is provided with a central longitudinal slot 3. A carrier bar 4 is disposed normally within the slot 3 and the ends of the said bar are turned upwardly as shown at 5, to provide supporting arms, as clearly shown. Through the upper end of each arm 5 a pivot bolt 6 is 45 inserted and this bolt is also utilized to secure a holding plate 7 in position, additional bolts or rivets 8 being inserted through the lower portion of the said plate and the arm so as to secure the said plate against 50 turning. The pivot bolt 6 extends through the upper ends of links or pitmen 9 which 55 extend therefrom through the slot 3 at the ends thereof and have their lower ends pivoted to a treadle 10 which is fulcrumed upon the cross bars 11 connecting the legs 2, 60 as clearly shown. The treadle may be of any desired or convenient form and is illustrated as consisting of longitudinal bars 12 connected at their ends by cross bars 13 through which the fulcrum pins or bolts 14 65 are inserted to mount the treadle upon the cross bars 11, spacers 15 being provided around the said pivot pins or bolts between the cross bars of the table and the bars 13 of the treadle so as to maintain the spaced 70 relation of the same, as will be readily understood.

The holding plates 7 are provided one at each end of the carrier bar 4 and are adapted to support the ends of the box or crate. To 75 support the central partition when such partition is used, I provide a similar holding plate 16 which is mounted upon the carrier bar by an angle iron or L-shaped bracket 17 having its branches secured rigidly to the 80 plate and carrier bar respectively, as shown clearly in Fig. 2. Upon the upper side of the carrier bar are lugs or ears 18 which are disposed in pairs and between the members of each pair I pivotally mount one end of a 85 clamping arm 19 which extends upwardly and then longitudinally of the table so as to coöperate with one of the plates 7 or 16. The arms 19 are provided at their upper free ends with cross bars or heads 20 which are 90 adapted to bear against the ends of the box and hold the same firmly against the holding plates 7 while the intermediate clamping arm has pivoted to its free end a clamping plate 21 which is adapted to coöperate 95 with the holding plate 16 and clamp the partition of the box or crate against the same. It will, of course, be readily understood that the intermediate arm may be provided with a cross head similar to the cross head 20, but 100 inasmuch as the side or bottom of the box is more apt to yield to the blows of the hammer during the nailing operation, I prefer to employ the plate 21 which will bear at its lower edge upon the table and thereby aid 105 in supporting the side or bottom of the box against such yielding or springing action. The arms 19 are held normally toward the coöoperating holding plates 7 or 16, as the case may be, by coiled springs 22 each of 110 which is attached at its lower end to the carrier bar 4 and at its upper end to the clamp-

ing arm near the free end thereof, the springs being disposed at an inclination, as shown clearly in Fig. 2, so that the pull exerted by them will serve to draw the clamping arms against the respective coacting plates.

The construction and arrangement of the several parts having been thus made known, it is thought that the operation of the machine will be readily understood. When a 10 box is to be formed, the ends of the same are placed on edge upon the table across the longitudinal slot therein and against the respective plates 7, the clamping arms 19 being swung manually away from the 15 said plates to permit the insertion of the box. As will be readily understood, upon release of the clamping arms the springs 22 will draw the same securely against the box ends so that they will be supported in vertical 20 position and the side or bottom of the box may be placed over and upon the upper edges thereof. A similar operation will, of course, support the central partition of the box or crate. The box ends and partition 25 having been thus arranged in an upright position and properly spaced apart, the bottom or one side is placed upon the upper edges of the partition and box ends and nailed thereto in the usual manner. When 30 the one side or bottom has been thus secured, the treadle 12 is depressed so that the pitmen 9 will be moved upwardly and the carrier bar 4, with the partly finished box still in place, will be raised above the table, after 35 which the bar and the parts supported thereon may be swung about the pivots 6 so as to bring another side of the box uppermost, whereupon the treadle is released and the partly finished box permitted to descend so 40 that the then lower edges of the partition and the box ends will rest upon the table. This action will be readily understood upon reference to the full and dotted lines in Fig. 3. After one side and the bottom have been 45 secured in place, the box is reversed so that the remaining side may be secured in place, after which the clamping arms 19 may be withdrawn from their working positions so as to permit release of the box or crate. The 50 top of the box or crate is, of course, not secured thereon until after the fruit, vegetables or other commodity have been placed therein.

It will be readily noted that I have provided an exceedingly simple and inexpensive machine which will firmly support the box

ends and partition while the sides and bottom are being secured thereto and will permit the parts to be readily and rapidly brought into the proper relative positions 60 and turned as may be necessary to complete the box. The machine is composed of very few parts and may be produced at a low cost while it will be found highly convenient in use for the purposes for which it is 65 designed.

Having thus described the invention, what is claimed as new is:

1. The combination of a carrier bar, means for supporting the same for pivotal and vertical reciprocatory movement, fixed clamping members on said bar and extending laterally from the opposite sides of the same, clamping arms pivotally mounted upon the bar and extending longitudinally 75 thereof with their free ends spaced from the bar to coact with said fixed clamping members, and yieldable means carried by the bar for drawing said movable clamping members to the fixed clamping members. 80

2. The combination of a carrier bar, means for supporting said bar for pivotal and vertical reciprocatory movement, fixed clamping members on said bar extending across the same and laterally beyond the 85 opposite sides thereof, clamping arms extending longitudinally of the carrier bar and each pivoted at one end to the carrier bar and having its free end spaced from the bar to coact with a fixed clamping member, 90 and coiled springs each attached at one end to the carrier bar adjacent a fixed clamping member and at its opposite end to the free end of the pivoted clamping arm.

3. The combination of a table having a 95 central longitudinal slot, a treadle arranged below the table, pitmen rising from the treadle and playing through said slot, a carrier bar extending between and pivoted at its ends to the upper ends of the pitmen, 100 plates fixed to said carrier bar and extending across and beyond the sides of the same, arms pivoted to the carrier bar and extending away from and longitudinally of said bar, cross heads at the free ends of said 105 arms, and springs secured at their opposite ends to the carrier bar and to said arms, respectively, adjacent the plates fixed to the carrier bar.

In testimony whereof I affix my signature. 110

RUBEN H. BOYCE. [L. S.]
